(57) **CLAIM**

The ornamental design for a shingle roof panel, as shown and described.

DESCRIPTION

FIG. 1 is a perspective view of a shingle roof panel in accordance with our design;

FIG. 2 is another perspective view of the shingle roof panel in accordance with the embodiment of our design;

FIG. 3 is a top plan view of the shingle roof panel in accordance with the embodiment of our design;

FIG. 4 is a front elevation view of the shingle roof panel in accordance with the embodiment of our design;

FIG. 5 is a left side elevation view of the shingle roof panel in accordance with the embodiment of our design;

FIG. 6 is a right side elevation view of the shingle roof panel in accordance with the embodiment our design;

FIG. 7 is a back elevation view of the shingle roof panel in accordance with the embodiment of our design; and,

FIG. 8 is a bottom plan view of the shingle roof panel in accordance with the embodiment of our design.

The broken lines showing environmental structure are for illustrative purposes and form no part of the claimed design.
